(57) **CLAIM**

The ornamental design for a smart watch, as shown and described.

DESCRIPTION

FIG. 1 is a front perspective view of a smart watch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged perspective view thereof, taken from encircled portion 9 in FIG. 1; and,

FIG. 10 is an enlarged perspective view thereof, taken from encircled portion 10 in FIG. 2.

The broken lines in the drawings illustrate portions of the smart watch and form no part of the claimed design. The dot-dot-dash broken lines encircling a portion of the smart watch in FIGS. 1, 2, 9, and 10 are included to show a partially enlarged view only and form no part of the claimed design.
